UNITED STATES PATENT OFFICE.

CHARLES A. HUMPHREYS, OF ERIE, PENNSYLVANIA, ASSIGNOR TO PITTSBURGH FILTER MFG. CO., OF PITTSBURGH, PENNSYLVANIA, A CORPORATION OF PENNSYLVANIA.

LIQUID-SAMPLE DEVICE.

1,174,156.

Specification of Letters Patent.

Patented Mar. 7, 1916.

Application filed March 19, 1914. Serial No. 825,913.

To all whom it may concern:

Be it known that I, CHARLES A. HUMPHREYS, a citizen of the United States, and resident of Erie, in the county of Erie and 5 State of Pennsylvania, have invented a new and useful Improvement in Liquid-Sample Devices; and I do hereby declare the following to be a full, clear, and exact description thereof.

10 My invention relates to apparatus for obtaining samples of liquid and is particularly, though not exclusively, adapted for taking liquid samples from the effluent pipe of a filter.

15 The object of the invention is to provide convenient means whereby a sample may be taken at any time by the operator standing at convenient location, for example, on the working gallery of the filter plant. It is to 20 be understood, however, that the inventive idea may be applied to other uses.

This invention covers an improvement on the apparatus shown in my co-pending application, Serial Number 683,299, filed 25 March 12th, 1912.

In the drawings which illustrate a preferred embodiment of the invention, Figure 1 is a fragmentary sectional view showing the position of the parts when the device is 30 not in use. Fig. 2 is a complete sectional view, showing the parts in position for filling the sample globe or receptacle. Fig. 3 is a view similar to Fig. 1, showing the parts in position to deliver the liquid sample. 35 Fig. 4 is a view showing the apparatus in conjunction with a filter, and Fig. 5 is a horizontal sectional view of the valve or cock plug for operating the device.

In the embodiment of the invention herein 40 selected for illustration, and referring particularly to Fig. 4, 1 indicates a filter chamber having the effluent pipe 2 and the cut-off valve 3 operable in the usual manner. From the effluent pipe a sampling pipe 4 extends 45 upward through a floor 5 to the working gallery of the plant, and to the sampling device which is conveniently mounted on a stand 6. The sampling pipe enters a valve or cock-head 7, provided with the rotatable 50 plug 8 having a handle 9. Also leading up through the stand 6 is a pipe 10 which may be connected with a convenient vacuum pump. The cock-head is provided with the usual spout 11.

55 A cock-plug is provided with a passage

12, a second passage 13 and a leak passage 14, as indicated in Figs. 1, 2, 3, and 5. A valve head is provided with a passage 15 communicating with the sample pipe 4, and a second passage 16 communicating with the vacuum pipe 10. At the upper end of 60 the valve head is a passage 17 arranged to register with the passages in the cock-plug when the latter is turned into certain positions, and also with a passage 18 which communicates with the exhaust pipe 19 leading up into the sample globe or receptacle 20 mounted upon the valve head. This globe may be of glass so that the height of the liquid therein may be observed, and also so 65 that the liquid may be sighted to determine its clarity. In the stand 6 is also mounted a drip pan 21 communicating with a waste pipe 22.

When the device is not in operation, the 70 cock-plug stands in the position shown in Fig. 1, wherein all of the passages therein are out of communication with the passages of the valve head. In order to secure a sample, the cock-plug is turned in the position shown in Fig. 2, wherein the passage 12 is brought into communication with the sample pipe 4 and with the interior of the globe 20 at the lower end. The passage 13 is simultaneously brought into communication 75 with the vacuum pipe 10 and with the passage 18 of the valve head, leading into the suction or exhaust pipe 19 within the globe 20. This pipe 19 as shown in Fig. 2, extends almost to the top of the globe. In 80 this position of the parts, the water or other liquid from the effluent pipe 2 will be drawn up by suction through the pipe 4 and into the globe 20 until it fills the globe to the level of the top of the pipe 19. The cock 85 plug may then be turned to the position shown in Fig. 3, whereby passage 13 connects the passage 17, communicating with the globe, with the spout 11 and the leak passage 14 is brought into communication with the valve 90 head passage 18 leading to the exhaust pipe 19 within the globe. Obviously, therefore, the water drawn up into the globe as before described, may flow from the globe 20 out through the spout 11, the water being replaced by air passing up through the leak 95 passage 14 and the pipe 19. At the same time, the vacuum connection is entirely shut off as will be seen from Fig. 3. It will be 100 seen, therefore, that so long as water flows 105 through the spout 11, the water being replaced by air passing up through the leak passage 14 and the pipe 19. At the same time, the vacuum connection is entirely shut off as will be seen from Fig. 3. It will be 110

in the effluent pipe 2 from the filter or other receptacle, a sample may be readily taken at any time by merely turning the cock to the proper position. The apparatus, therefore, may be at all times in operative condition by connecting the pipe 10 with a constant vacuum source.

While I have herein described a particular embodiment of the invention, it is to be understood that it may be altered in details and in arrangement of parts within the scope of the appended claims.

What I claim is:

1. A liquid sampling device comprising a valve head having a passage communicating with a source of liquid, a second passage communicating with a source of vacuum, a sample receptacle mounted upon said valve head, a passage in said head communicating with the bottom of said receptacle, a second passage communicating with the top of said receptacle, said valve head having a spout, a rotatable cock having a plurality of transverse passages and having a leak passage constantly open to the atmosphere, said passages being so relatively arranged that upon turning the cock to proper positions, the liquid supply and vacuum pipes may be entirely shut off, or the liquid supply pipe may be brought into communication with the bottom of the receptacle and the vacuum pipe with the top

of the receptacle, and finally whereby the bottom of the receptacle may be brought into communication with the spout and the top 35 of the receptacle may be brought into communication with the atmosphere.

2. In a liquid sampling device, the combination with a source of liquid having an effluent pipe, an operator's stand conveniently located with respect to said liquid source, a valve head mounted on said stand, a liquid sampling receptacle mounted on said valve head, a pipe connecting said valve head and source of liquid, a second pipe connecting said valve head and a source of vacuum, a cock rotatably mounted in said valve head and provided with passages so arranged that the lower and upper ends of said sample receptacle may simultaneously 50 be brought into communication with said liquid source and said vacuum pipe respectively, and upon turning said cock, the bottom of said sample receptacle and the top thereof may be brought respectively, simultaneously into communication with a discharge spout and the atmosphere. 55

In testimony whereof, I the said CHARLES A. HUMPHREYS have hereunto set my hand.

CHARLES A. HUMPHREYS.
